UNITED STATES PATENT OFFICE.

OTTO EICK, OF BALTIMORE, MARYLAND.

BOTTLE-CLEANING APPARATUS.

1,292,278.

Specification of Letters Patent. Patented Jan. 21, 1919.

Application filed November 22, 1912. Serial No. 732,969.

To all whom it may concern:

Be it known that I, Otto Eick, a citizen of the United States, residing at Baltimore, in the State of Maryland, have invented certain new and useful Improvements in Bottle-Cleaning Apparatus, of which the following is a specification.

My present invention pertains to improvements in bottle-cleaning apparatus, the construction and advantages of which will be hereinafter set forth, reference being had to the annexed drawings, wherein:

Figure 1 is a longitudinal sectional elevation of the mechanism;

Fig. 2 a top plan view thereof; and

Fig. 3 a transverse sectional view, taken on the line 3—3 of Fig. 1.

The main object of the invention is to provide a simple and compact apparatus wherein the bottles will be cleaned both interiorly and exteriorly, and the labels which are removed therefrom collected from the cleansing liquid and discharged from the machine.

A further object of the invention is to so construct the apparatus that a single attendant may insert the bottles to be cleaned and at the same point or station remove those which have been cleaned in their passage through the machine.

Another object of the invention is to provide means for drawing off the vapor which emanates from the heated cleansing liquid, and to also provide suitable mechanism whereby all the operative parts may be driven from a single motor, thus enabling the machine to be started and stopped in all its parts at will. Said motor may be under the direct control of the operator who inserts and removes the bottles.

Stated in broad terms, the structure may be said to comprise a tank in which the bottles are immersed in a cleansing fluid and subjected to a cleansing spray, an endless way passing through the tank and over the same for supporting the bottles and causing them to pass through the apparatus, together with mechanism adapted to subject the bottles, after they pass out of the tank, to a brushing and spraying action.

In the drawings, 1 denotes a tank, having at that end which may be termed the intake and discharge end, an elevated section 2, and at the opposite end a similar section 3, the latter being surmounted by a hood or housing 4. A pan 5, is formed intermediate the

elevated ends 2 and 3, and a pan 6 is located adjacent to the discharge opening formed at the inner end of the hood or housing 4. Secured upon the opposite vertical walls of the tank and housing 4 are a pair of tracks 7, which form a continuous way in which roller chains 8 and 9 find their bearings, said chains being connected to each other by cross-bars 10, thereby producing in effect an endless carrier which extends through the tank and the elevated portions 2 and 3 thereof, through the housing 4 and outwardly therefrom over a brushing and rinsing mechanism, and thence back to the entrance to the elevated portion 2 of the tank. This carrier is designed to hold racks, as 11, in which the bottles may be placed by the attendant, say, at the point indicated by A in Fig. 1, which point may be termed the filling and discharge station. The racks 11 are preferably made of metal and are of such size as to fit between the cross-bars 10 of the carrier, the ends of the racks finding their bearings in oppositely-disposed U-shaped guides or ways 12 which are co-extensive with the endless way in which the chains move.

The bottles are designed to be placed in the racks with the mouths innermost, and to prevent the bottles from dropping out of the racks as they pass through the tank, suitable bars 13 and 14 are placed in series in the tank, the bars being so spaced as to be in alinement with the bottoms of the bottles which are passed over the bars in their travel through the tank.

To advance the carrier step by step I provide a carriage 15, Fig. 1, mounted upon suitable ways or tracks 16, said carriage having a pivoted pawl or dog 17, the dog depending from the carriage to such an extent that it will engage the cross-bars 10. When the parts are in the positions shown in Fig. 1, it will be seen that the dog 17 is in contact with one of the bars and as the carriage is moved forwardly through the mechanism which will be later set forth, it will advance the carrier a step forward, for a distance equal to the space between two of the cross-bars. As the carrier moves rearwardly from its advanced position, the pawl or dog 17 will ride over the next bar to the rear and then drop so as to engage the same as the carriage is again moved forward. Thus it will be seen that the carrier and the racks in engagement therewith will be

moved forward step by step intermittently, and while the carrier is at rest the attendant will remove the clean bottles from the racks and insert bottles which are to be treated.

5 The tank is designed to contain any cleansing liquid, such for instance, as a soda solution, and it will preferably be hot.

Overlying the elevated portion 2 is a hood 18, adapted to receive the vapors or fumes 10 arising from the solution and to convey the same from the apparatus through suitable exhaust mechanism.

In the passage of the bottles through the tank the dirt and other material will be loosened and the labels will likewise be loosened, and in order that the labels may be washed off in case they still adhere when the bottles rise above the level of the cleansing fluid in the portion 3 of the tank, I provide means 15 for spraying the bottles. To this end I employ a centrifugal pump 19, the intake of which is connected with a pipe 20, which pipe in turn is connected with a branch 21 opening into the interior of a rotating perforated drum 22 mounted in the tank section 3. The upper portion of the drum will be approximately on a level with the surface of the water in the tank. A pipe 23 extends from the pump 19 and terminates in spray 25 pipes 24 and 25, the pipe 24 first ejecting water against the lower or mouth portions of the bottles and pipe 25 thereafter spraying the bottoms of the bottles which are then, as indicated in Fig. 1, in an inverted position.

The suction of the pump 19 causes a current to be set up in the fluid in the tank and consequently the labels will be drawn against the drum from which they will be 40 removed by a scraper or doctor 26. The cleansing fluid is thus kept free of labels and the rotary drum acts as a screen to prevent the entrance of material into the pump which would tend to clog the same, and likewise 45 tend to clog the spray pipes 24, 25.

The tank will, of course, be discharged from time to time, and the solution renewed through suitable pipes. Clean-out doors, as 50 27, will also be provided.

55 A hinged deflector plate 26^a overlies the drum and prevents the cleansing fluid from splashing out of the opening which is formed in the wall of the housing above the scraper 26. A second fixed guard 26^b overlies the hinges of the deflector plate 26^a so as to prevent the water or other fluid from passing down through the joint between the member 26^a and the housing. The labels will be removed from the scraper 26 from time to 60 time, and inasmuch as the opening in the housing is guarded at this point the attendant will not be subjected to the splash of any of the cleansing fluid.

Just prior to the passage of the bottles 65 from the housing 4 they are subjected to a

spray of clean water through a pipe 28, said pipe occupying a position in the upper portion of the housing and discharging water directly onto the bottles, the water passing through the pan 6 heretofore referred to, 70 and thence into a pipe 29, to a discharge pan 30. Said pan is connected with an outlet pipe 31, which discharges to the sewer at any suitable point. The water is supplied to the spray pipe 28 through a pipe 32, connected to one side of a pump 33, the opposite side of the pump being connected by a pipe 34 to the pan 5, heretofore referred to. The water is fed to the pan 5 from the bottle-rinsing and brushing mechanism, which is 75 located thereover. Said rinsing and brushing mechanism is shown in Fig. 1, and may be said to comprise heads 35, fixed to uprights 36, which take the form of hollow columns, said heads having secured thereto 80 spray pipes 37. Sliding heads 38, are likewise mounted upon the columns 36 and carry the brush spindle box 39. Suitable counterweights are mounted in the columns 36 and cords or cables 40 are connected thereto and 85 pass over pulleys 41 mounted at the head of the columns and around pulleys 42 and 43 (Fig. 1), and to the heads 38, to which they are securely fastened. The heads 38, with the spindle box 39, are designed to be moved 90 up and down upon the columns so as to pass the brushes into the bottles while they are at rest thereover, and to this end a rod or pitman 44, connected to a crank arm 45, is connected with the driving mechanism of the 95 machine. Said mechanism receives its power from a motor 46 preferably an electric motor, from which extends a belt 47, that passes around a driving pulley 48, mounted upon a shaft 49. Said shaft carries a pinion 50, meshing with a gear 51, mounted upon a shaft 52. The opposite end of the shaft carries a pinion 53 which meshes with a relatively large gear 54 mounted upon a shaft 55. Said shaft at its opposite end carries a 100 pinion 56 which in turn meshes with a gear 57. Said gear is mounted upon a shaft 58, the shaft likewise having secured to it a crank-arm 59, to which is attached a rod or pitman 60, connected to the sliding carriage 105 15 hereinbefore referred to. Shaft 58 also carries a pinion 61, which in turn meshes with a similar pinion 62 mounted upon a shaft 63, said shaft carrying a sprocket-wheel about which passes a sprocket-chain 110 64. The chain likewise passes about a relatively large sprocket-wheel 65, connected to the shaft of the drum 22.

Motion is imparted to the crank arm 45 hereinbefore referred to, through intermittent gears 66 and 67 or other suitable means. It will thus be seen that the carriage 15 is given a constant to and fro motion and the drum 22 is likewise constantly, somewhat slowly rotated.

The brush spindle box will be held at rest in its lowermost position while those bottles which have been cleaned are being moved away from over the same, and a new set of 5 bottles is being presented, and after they come to rest the spindles will be elevated and brought into action.

The machine, as before indicated, is automatic in its action, and it is only necessary 10 that the attendant remove the clean bottles from the racks and recharge said racks prior to the descent thereof into the cleaning solution within the tank.

The label-extractor as shown herein is 15 capable of wide application and may be employed with any type of washing machine susceptible of receiving the same. So, too, while the liquid which is drawn through the extractor is described as being returned to 20 the tank, it will be understood that it may be discharged elsewhere; in other words, generally speaking, the invention is not to be limited to the details shown and described.

Having thus described my invention, what 25 I claim is:

1. In a bottle-cleaning apparatus, the combination of a tank; means for passing bottles therethrough; a rotary label-extractor mounted therein; and means for subjecting the 30 bottles as they pass through the apparatus to the action of a cleansing fluid drawn from the tank.

2. In a bottle-cleaning apparatus, the combination of a tank; means for passing bottles 35 therethrough; a rotary label-extractor located therein; means for removing the labels from the extractor; and means for subjecting the bottles as they pass through the apparatus to the action of a cleansing fluid drawn from 40 the tank.

3. In a bottle-cleaning apparatus, the combination of a tank; means for passing bottles therethrough; a rotary perforated drum located therein and adapted to gather labels 45 from the fluid within the drum; means for removing the gathered labels from the drum; and means for subjecting the bottles as they pass through the apparatus to the action of a cleansing fluid drawn from the tank.

4. In a bottle-cleaning apparatus, the combination of a tank; means for passing bottles therethrough; a perforate body movable through the liquid within the tank; means for causing the liquid to pass through the 55 body, whereby labels and the like removed from the bottles will be collected on said body; and means for ejecting such cleansed liquid upon the bottles as they pass through the apparatus.

5. In a bottle-cleaning apparatus, the combination of a tank; means for passing bottles therethrough; a rotary perforate drum

mounted therein and adapted to move through the liquid contained within the tank; means for drawing the liquid inwardly into the drum; and means for ejecting the liquid which is drawn through the drum onto the bottles as they pass through the apparatus.

6. In a bottle-cleaning apparatus, the combination of a tank; means for passing bottles therethrough; a rotary perforate drum mounted therein and adapted to move through the liquid contained within the tank; means for drawing the liquid inwardly into the drum; means for removing the labels and the like from the surface of the drum; and means for ejecting the liquid drawn through the drum onto the bottles as they pass through the apparatus.

7. In a bottle-cleaning apparatus, the combination of a tank; a perforate drum located therein; means for revolving said drum; a spraying device located in the tank above the level of the cleansing fluid therein; and means for withdrawing the cleansing fluid from the interior of the drum and forcing it from the spraying device.

8. In a bottle-cleaning apparatus, the combination of a tank; an endless bottle-carrier 90 extending through the tank in a substantially elliptical path; a rotary perforate drum located within the tank and between the upper and lower run of the carrier; a spraying device located adjacent to the carrier; and means for drawing the cleansing fluid through the drum from the tank and forcing it through the spraying device.

9. In a bottle-cleaning apparatus, the combination of a tank having high end portions and a relatively low central portion; an endless bottle-carrier extending through the tank in a substantially elliptical path; a label-extractor located within the tank in one of the high portions thereof and between the upper and lower run of the carrier; a spraying device located within the tank; means for withdrawing the liquid from within the extractor and forcing it to the spraying device; a final liquid cleaning mechanism located adjacent to the discharge point of the tank; a receptacle adapted to receive the liquid passing from said cleaning mechanism; and means for removing the liquid from said receptacle and spraying it on the bottles as they pass from the tank to the final cleaning mechanism.

In testimony whereof I have signed my name to this specification in the presence of two subscribing witnesses.

OTTO EICK.
